UNITED STATES PATENT OFFICE.

STANLEY KUPKA, OF CHICAGO, ILLINOIS.

INDUCTANCE.

Application filed July 25, 1925. Serial No. 46,097.

My invention relates to improvements in inductance, and it consists in the combinations, constructions, and arrangements herein described and claimed.

5 An object of my invention is to provide an inductance of the character described which is particularly well adapted for use in radio circuits, and in which the winding is so arranged as to minimize the effective 10 electromagnetic field about the inductance, whereby two or more of the inductances constructed in accordance with my invention, may be placed in close proximity with one another, regardless of position, without 15 appreciably altering the internal resistance of the inductance.

A further object of the invention is to provide an inductance of the character described in which the internal capacity of 20 the inductance is reduced to a minimum.

A further object of my invention is to provide a device of the character described which is simple in construction, compact in form, and thoroughly practical for the 25 pose intended.

Other objects and advantages will appear in the following specification, and the novel features of the invention will be particularly pointed out in the appended claim.

30 My invention is illustrated in the accompanyings forming part of this application, in which

Figure 1 is a perspective view of an embodiment of my invention, and

35 Figure 2 is a diagrammatic view illustrating the arrangement of the winding of the inductance.

In carrying out my invention I make use of a short tubular insulating member 1 upon 40 which the inductance is wound. This member is similar in appearance and structure to the ordinary supporting member upon which the well known type of tuning coil employed in radio circuits is wound.

45 The winding of my improved inductance consists of a single wire having a terminal 2 projected through an opening 3 adjacent to one end of the member 1. The wire is wound diagonally across the outer surface 50 of the member as shown at 4, then through

the central opening of the cylindrical member, diagonally across the inner surface as shown at 5, and back over the edge upon the outer surface, whereupon the same arrangement is carried out until the wire has 55 reached the point 6. This same arrangement is carried out to form a second disposition of the winding parallel to the first. This is continued until the proper length of wire has been wound in the inductance. The 60 outermost end or opposite terminal 7 is projected through an opening 8 at the opposite end from the opening 3 and the entire device is emerged in insulating material, such as shellac or the like to hold the winding 65 in place. If it is not desired to employ a cementitious medium to hold the windings in place they may be wound sufficiently tight to hold without such medium.

In Figure 2 I have shown the arrangement of the winding, the succeeding turns to the first being indicated at 9.

From the foregoing description of the various parts of the device the operation thereof may be readily understood. Due to the peculiar disposition of the turns upon the member 1, the effective electromagnetic field about the device is minimized, and two or more of the inductances may be placed in close proximity with one another, regardless of the positions with respect to one another, without appreciably impairing the internal capacities or resistances of the several windings.

70 For this reason my improved inductance 85 is especially well adapted for use in radio circuits.

I claim:

An inductance comprising a tube formed of insulating material, and a wire having 90 one end project through an opening in said tube, said wire being wound around said tube and having the other end project through another opening in said tube, the 95 windings of said wire forming groups of wire portions disposed diagonally across the outer and inner surfaces of said tube, said groups being spaced apart.

STANLEY KUPKA.
